UNITED STATES PATENT OFFICE.

HARRY E. TUNNELL, OF NEW YORK, N. Y., ASSIGNOR TO FIRE GUN MANUFACTURING COMPANY, INC., OF NEW YORK, N. Y., A CORPORATION OF NEW YORK.

LIQUID PROJECTOR.

Application filed January 18, 1919. Serial No. 271,830.

To all whom it may concern:

Be it known that I, HARRY E. TUNNELL, a citizen of the United States, and resident of the borough of Manhattan, city, county, 5 and State of New York, have invented certain new and useful Improvements in Liquid Projectors, of which the following is a specification.

My invention relates to devices for projecting liquids in the form of a jet or spray, and while intended primarily for the discharge of fire-extinguishing liquids, is susceptible of other uses, such as the spraying of plants, the application of paints or cleaning liquids, etc.

The object of my invention is to simplify in many respects, an apparatus of the class indicated above, with a view of reducing the cost of manufacture and of obtaining a construction of great certainty and efficiency of operation, and particularly, it has been my aim to reduce the number of pipes employed in the apparatus. For this purpose, I have devised an arrangement in which certain 20 pipes act alternately as suction pipes and as delivery pipes for the pump forming part of the apparatus; other features of the invention will be set forth fully in the description following hereinafter and in the 25 appended claims.

Reference is to be had to the accompanying drawings, in which Fig. 1 is a longitudinal section of the apparatus on line 1—1 of Fig. 2; Fig. 2 is a longitudinal section taken substantially on line 2—2 of Fig. 1; Fig. 3 is a partial transverse section on line 3—3 of Fig. 2; Fig. 4 is a partial section of the parts at the upper left-hand portion of Fig. 2, taken in the same plane as Fig. 2, but with the parts in a different position; Fig. 5 is a longitudinal section on the line 5—5 of Fig. 3, showing the parts in a position corresponding to the one of the parts in Fig. 4; Fig. 6 is a longitudinal section of the valve casing, substantially on line 6—6 of Fig. 7; Fig. 7 is a detail transverse section on the line 7—7 of Fig. 6; Fig. 8 is a face view of two spring washers fitted on the piston rod of the pump, said rod being shown in section; Fig. 9 is a face view of a stop limiting the movement of certain valves; Fig. 10 is a partial bottom view of the interior parts; and Fig. 11 is an end view of one of the swinging intake tubes.

55 The apparatus illustrated in the drawings

is composed of a container for the liquid to be projected, and a pump located within the container and adapted to expel the liquid therefrom. The container comprises a shell 20, of cylindrical or other suitable shape, and two heads 21, 22 respectively, preferably of spherical curvature, as will be explained hereinafter. The pump is preferably located at one side of the container, and is composed of a barrel 23 one end of which is set tightly into a suitable casing 24 engaging the shell 20 as shown in Fig. 2 and also engaging the inturned edge or flange 21' of the head 21 at an opening thereof. On the outside of the flange 21' lies a plate 25 formed with a central sleeve 25', and adjacent thereto lies a suitable locking device, which may consist of a flange 26, interrupted as indicated at 26' (see Fig. 1) to allow the passage of a suitable projection 27' on the handle 27 of the pump, said handle being locked against longitudinal movement when the projection 27' has been turned out of registry with the gap or opening 26', with the handle in its innermost position. When the handle 27 is moved fully inward, the free edge of the sleeve 25' engages a washer 28 situated in a recess 27'' of the handle, thereby securing a tight joint when the handle is in the locked position.

The casing 24 is made with a passage 24' and with a duct 24'' which communicates with said passage and also with a pipe 29 extending lengthwise of the container, adjacent to the barrel 23. On the outside of the passage 24', the casing 24 is formed with a chamber 24* containing packing means for obtaining a liquid-tight joint while providing a vent for the entrance of air into the container as the liquid is being expelled therefrom. This means comprises a box 30 screw-threaded into the outer end of the chamber 24* and fitted against a shoulder of the casing 24 adjacent to the passage 24'; this inner end of the box has a central perforation for the passage and guidance of the piston rod 31, to the outer end of which the handle 27 is secured. The inner end of the box 30 is formed with a preferably curved seat for a washer 32 made of asbestos felt or other suitable material. The outer surface of this washer is engaged by a cup-shaped washer 33 of spring metal, and a similar elastic washer 34 is fitted within the box 30 adjacent to the washer 33, these

two metal washers being fitted with their convex surfaces toward each other. At its central portion, each of the washers 33, 34 is made with an opening 33', 34' of elongated or 5 other non-circular shape, so that the annular space 24^a of the chamber 24* will always be in communication with the portion of the chamber immediately adjacent to the piston rod 31. In Fig. 8 the two openings or slots 10 33', 34' are shown out of alignment longitudinally of the piston rod, but even if the washers 33, 34 should be given a position in which said slots will be in longitudinal alignment, there would still be left a passage 15 from the space 24^a to the space immediately adjacent to the piston rod, since owing to the non-circular shape of said slots and the convexity of the washers, the edges of one slot could never be in contact with the edges of 20 the other slot along its entire outline.

Exteriorly of the cup-shaped washer 34, the chamber 24* contains another washer 35 of felt or other material loose enough to allow air to pass therethrough, and the outer face 25 of this washer 35 is engaged by the concave inner face of a gland 36 screwed into the outer end of the box 30 and having a tubular projection extending into the sleeve 25'. The spring washers 33, 34 are put under tension by the pressure of the gland 36, so as to properly expand the soft washers 32, 35 into good engagement with the walls of the chamber 24*. While the piston rod 31 has a sliding fit in the gland 36 and in the 35 washers 34, 35, such fit is sufficiently loose to provide an air-passage or vent from the surrounding air to the space 24^a, for the purpose more fully set forth hereinafter. The box 30 is spaced at its inner portion from the cylindrical wall of chamber 24*, thus forming an annular space in permanent communication with the space 24^a, through one or more ducts 30', and also with the interior of the container, through one or more channels 24^b, arranged preferably at the lower 40 portion of the chamber 24*.

The end of the pipe 29 opposite to the casting 24 is connected with the section 37 of a valve casing located at the central portion 45 of the pump. This section has an L-shaped channel 38 in permanent communication with the pipe 29 and therefore with the upper or outer compartment of the pump barrel 23. From said channel 38 a duct 38' leads to a seat for a ball valve 39, and another duct 38'' leads to a port provided with a stop 40 for a ball valve 41. The valves 39 and 41 are contained in a second section 42 of the said central valve casing, 50 the edge of said second section being crimped, as at 42', to connect it securely with the section 37. The ball valve 41 is adapted to engage guide ribs 42'' of the section 42, the circle or cylinder which contains the inner edges of the ribs 42'' being

sufficiently larger than a great circle of the ball 41 to insure engagement of said ball with no more than two ribs at a time (as shown in Fig. 7), over an angle of less than 180°, thereby insuring a proper guiding of 70 the ball valve, and preventing it from getting stuck or jammed between said ribs. Preferably five ribs are employed, at even distances apart. As shown in Fig. 7, the ribs are tapered toward their free or inner edges, so that at any one time, the engagement of the ball with a rib will be at a single point, and the path of such point of contact or engagement will accordingly be along a single line. Between said ribs 42'', the section 42 is 75 formed with a chamber 43, in permanent communication with the channel 38. At the inner end of the chamber 43 there is a seat for the valve 41, the latter, when seated as shown in Fig. 6, closing the communication 80 from the chamber 43 to a longitudinal passage 44 in the section 42. At the opposite end of the passage 44 is located an enlargement or chamber 45 similar to the chamber 43, with ribs 42* similar to the ribs 42''. The ribs 42* form guides for a ball valve 46 85 similar to the valve 41 and adapted to become seated at the junction of the chamber 45 with the passage 44. The central portion of this passage is connected, by a transverse duct 44' contained in a tubular lateral extension 42^a of the section 42, with a longitudinal passage 44'' in a portion 42^b of the section 42. At the ends of said passage are 90 provided seats for ball valves 47, between which is interposed loosely a separator 48, of such length that when one of the balls 47 is seated, the other ball will be off its seat. Externally of the valve seats, the portion 42^b is provided with longitudinal 95 guide ribs 42^c, of the same character as the ribs 42'', 42*. The outward movement of the balls 47 is limited by stops 49 fitted into enlargements at the outer ends of the portion 42^b. As shown in Figs. 6 and 9, each of the 100 stops 49 is provided with a concave seat on the side facing the respective ball 47, and preferably a point 49' projects from the center of said seat to engage the ball valve when it is in the position illustrated at the lower 105 portion of Fig. 6, and thus to prevent the ball from engaging the seat along a material portion of its surface, which surface engagement might result in a sticking of the ball. The seat portion of the stop 110 49 is connected with the body portion thereof by ribs 49'' between which are formed openings 49* for the passage of the fluid, the stops 49 being tubular, at their outer portions. Sleeves or thimbles 50, 115 fitted into the enlargements containing the stops 49, hold said stops against shoulders in the portion 42^b, said thimbles being themselves held in place in any suitable manner, 120 preferably by crimping the edges of the por- 125

tion 42^b, as indicated at 42^d. The thimbles 50 contain suitable washers 51 (say of felt) in engagement with the outer surfaces of universally-rocking perforated balls 52, each connected rigidly with a swinging intake pipe 53. These pipes are preferably weighted, as at 54, to cause them to swing more readily by gravity, each pipe taking the lowest position that the position and shape of the container will allow. The weights 54 are sleeves which may be held securely on the respective pipes 53 by pressing the metal inward, as at 54', thus nicking the sleeve 54 and at the same time possibly slightly deforming the pipe 53 at that point. As a further safeguard against movement of the sleeve 54 relatively to the pipe 53, the latter may be of circular cross section in its main portion, but slightly oval or flattened at the free end so that one of its diameters will be slightly larger than the diameter of the sleeve opening, as indicated in Fig. 11.

The central valve casing also comprises a third section 55 adapted to fit against the face of the section 42 opposite to that engaged by the section 37. This section 55 has a surface groove 56 forming a transverse channel in conjunction with the adjacent surface of the section 42, and is also provided with a longitudinal duct 56' communicating with said channel 56 and with one end of a longitudinal channel 57 provided in the section 42, the other end of said channel 57 being provided with a seat for the ball valve 39, which is thus adapted to become seated either at the said end of the channel 57, or at the adjacent end of the duct 38'. The section 55 also has a stop 55' for limiting the movement of the valve 45 away from its seat. The connection of the section 55 with the section 42 is effected in any suitable manner, preferably by crimping the edge of the latter section, as indicated at 42^e. When formed as illustrated, the three sections 37, 42, and 55 may be readily produced as die-castings, and therefore at a comparatively low cost. The only operation required subsequently to the casting operation, would be the drilling of the transverse channel 44', its outer end being then closed by a plug 42^f, say of solder. The section 42 is also formed with a fork 42^g, adapted to straddle the pump barrel 23, as indicated in Fig. 3, so as to properly position the central valve casing relatively to the pump barrel.

The lower end of the duct 56' is connected with a pipe 58, shown in line with the pipe 29, and leading to a port 58' (Figs. 2 and 5) at the end of the barrel 23 opposite to the casing 24, said port being in a lower casing 59 into which the lower end of the pump barrel 23 is fitted, the port 58' therefore being in communication with the lower compartment of the pump barrel.

The lower edge of the casing 59 is crimped as at 59', to connect said casing with a sleeve 60, engaging the head 22 on its inner surface, and screw-threaded internally for connection with an outlet member 61 70 provided with an outwardly-extending nozzle 61' and also with an inwardly-extending tube 61''. The nozzle 61' is shown soldered to a plate 62 soldered to the outer surface of the head 22, the latter having an opening the edge of which is clamped between the said plate and the sleeve 60. In a recess on the inner face of the outlet member 61, and surrounding the tube 61'', is seated a washer 63, adapted to be engaged by the free edge of a cup-shaped member 64, which contains a washer 65 adapted to engage the inner end of the tube 61'', thus forming a double-seated valve having a double seal, see Fig. 2. A spring 66, coiled around the tube 61'', tends to force the cup or valve 64 away from the outlet member 61, and thus to open the valve. On its inner side, the valve 64 is provided with an axial tubular extension 64' surrounded by a spring 67 which normally tends to force away from said valve, a slide 68 having an axial stem guided in the tubular extension 64' and in the plate or partition 59'' located below the port 58'. The slide 68 is formed with a plate 68' forming a bearing or abutment for the upper end of the spring 67, and also adapted to engage a washer 69 and to press the same against the partition 59'', so as to form a tight 100 joint where the stem of the slide 68 passes through said partition, at such times when tightness of this joint is required by the conditions of operation, as explained hereinafter. The spring 67 is stronger than the spring 66. When the valve 64 is open, the nozzle 61' communicates with the chamber 70 in which said valve and the larger portion of the slide 68, 68' are arranged, and said chamber has a port 70' in permanent 110 communication with a pipe 71 leading to an angular channel 72 in the section 42 of the central valve casing; this channel is partly a surface groove co-operating with the adjacent surface of the section 37, 115 and leads to the two seats of the ball valve 39.

The inner or upper end of the sliding stem 68 is adapted to be engaged by the lower or inner end of the rod 31, said rod projecting beyond the piston 73 (Fig. 2).

The casings 59 and 24 are provided with guides 74 and 75 respectively, said guides being of the same shape and arrangement, which shape is shown best in Fig. 10.

It will be noted that the pipes 29, 58, and 71, as well as the pump barrel 23, extend in the same direction longitudinally of the container, so that these parts may be readily connected with each other and 130

with the end casings 24, 59, and the central valve casing 37, 42, 53, by fitting the said pipes into the corresponding sockets or openings and exerting pressure lengthwise of the pipes on the two end casings toward the central casing, the barrel 23 and the pipes being made of harder metal than the said casings with which they are connected.

- 10 It will further be seen that one of the compartments of the pump barrel 23 (the one nearest the handle 27) is in permanent communication with the pipe 29 and through it with what I may term an intermediate 75 chamber, which chamber consists of the channel 38, its ducts 38', 38'', and the chamber 43. Similarly, the barrel compartment on the other side of the piston 73 is in permanent communication, through the pipe 58, with another intermediate chamber consisting of the chamber 45, and the channels 56, 57 with the duct 56'. The channels 44, 44' and those in communication with the latter may be termed a suction chamber 80 common to both of the aforesaid intermediate chambers, and the channel 72 connected with the pipe 71 and with the chamber 70, may be termed an outlet chamber likewise common to both intermediate 85 chambers. The valves 39 and 41 open away from and toward the intermediate chamber connected with the pipe 29, and the valves 45 and 39 open inwardly and outwardly respectively with reference to the other intermediate chamber (the one connected with the pipe 58). The valve 39 controls the connection of the outlet chamber alternately with the two intermediate chambers.

When the apparatus is not in use, the handle 27 is pushed in fully until the projection 27', having passed through the gap 26' and having been turned under the flange 26, is locked by said flange against longitudinal movement. Such inward movement of the handle 27 also brings the inner end of the piston rod to a position (Fig. 2) in which the slide 68 is moved toward the nozzle 61' to a sufficient extent to seat the valve 64, thus preventing any leak at the outlet. The interposition of the spring 67 between the slide 68 and the valve 64 enables the valve to become properly seated notwithstanding any inaccuracies due to wear or to imperfect manufacture. The container is filled through a suitable opening which is then closed air-tight (without a vent-valve) by a solid plug 76 (Fig. 2).

In order to operate the apparatus, the handle 27 is first turned to bring its projection 27' into registry with the opening or gap 26', so that the handle and the piston 73 may now be given a reciprocating movement. Preferably, the handle is first moved outwardly until its projection 27' clears the flange 26, and is then turned slightly so that

said flange will form a stop in the path of the projection 27' so that at its inward stroke, the piston rod 31 will not reach the valve-closing position shown in Fig. 2. As soon as the handle is moved outwardly from the position indicated in Fig. 2, the compression of the spring 67 is relaxed, and as the outward movement of the piston rod continues, the spring 67 will be relaxed to a sufficient extent to allow the spring 66 to open the valve 64, see Fig. 5, thus establishing a free communication between the chamber 70 and the nozzle 61'.

As the handle 27 is reciprocated with the piston rod 31 and with the piston 73, the following operation takes place: During the inward stroke, the piston 73 (which is solid in the sense that it has no passage leading through it) exerts suction in the compartment connected with the pipe 29, and pressure in the compartment connected with the pipe 58. This suction causes liquid to pass into the barrel 23 through the pipe 29 from the channel 38, that is to say, from the intermediate chamber of which said channel forms part. Said suction causes the valve 39 to engage its upper seat, thus shutting off communication between said intermediate chamber and the outlet chamber formed by the channel 72. At the same time, said suction moves the valve 41 off its seat, thus establishing communication between said intermediate chamber and the channel 44 forming part of the suction chamber. This suction chamber is always in communication with the liquid-space of the container, since the gravity valves 47 will automatically take such a position that the upper one of them will be closed, so that the pipe 53 which at that time is the upper pipe, will be shut off from communication with the suction chamber. It will be obvious that when the container is but partly filled with liquid, its upper portion will contain air, and if the gravity valves 47 were omitted, there would be danger (with the arrangement of two pipes 53 shown) of sucking air into the pump together with liquid. The position of the gravity valves 47 depends on the position in which the container is held, but the action of the other parts of the apparatus is independent of the position of the apparatus. The pressure exerted by the piston 73 during the inward stroke will force liquid from the compartment having the port 58', through the pipe 58 into the duct 56' and channel 56, that is to say, into the other intermediate chamber of the central valve casing. This pressure, acting through the chamber 45, will force the ball valve 46 against its seat and thus shut off communication between said intermediate chamber and the suction chamber of which the channel 44 forms part. The liquid under pressure reaching said inter-

mediate chamber will therefore flow through the channel 57 into the channel 72 (assisting in keeping the valve 39 against the orifice of the duct 38'), and will then flow through 5 the pipe 71 and port 70' into the chamber 70, and out through the member 61 and its nozzle 61'. The pressure of the liquid in the chamber 70 will press the plate 68' against the washer 69, thus preventing communication of said chamber with the adjacent compartment of the barrel. It is true that at this particular stage of the operation, no harm would result if the chamber 70 did communicate with the adjacent 10 compartment of the pump barrel, but at certain other periods, as will be described presently, it is necessary to shut off the chamber 70 from the adjacent pump compartment.

15 During the outward stroke of the piston, pressure will be exerted in the pump barrel compartment connected with the pipe 29, and the liquid thus expelled from said compartment will pass through said pipe into the corresponding intermediate chamber, that is to say, into the channel 38, its ducts 38', 38'', and the chamber 43. This will force the valve 41 against its seat, thereby shutting off said intermediate chamber from 20 the channel 44 of the suction chamber. At the same time, the valve 39 will be forced away from the orifice of the duct 38' against its other seat (see position Fig. 5), thus connecting the outlet chamber (channel 72) 25 with said intermediate chamber, and disconnecting the outlet chamber from the other intermediate chamber (of which the channel 57 forms a part). The liquid will then pass to the chamber 70 and to the nozzle 61' as before, and the pressure in said chamber will cause the slide plate 68' to hold the washer 69 tightly against the partition 59'', so as to close tightly the joint between said plate and said partition, since 30 at this time there is suction in the pump compartment connected with the pipe 58, and if there was no tight joint where the stem of the slide 68 passes through the partition 59'', some liquid, instead of passing 35 from the chamber 70 to the nozzle 61', would be sucked from said chamber into said compartment of the pump barrel. During this outward stroke of the piston, liquid is sucked into said compartment through the pipe 58 from the intermediate chamber of which the duct 56' forms a part, the valve 39 being seated toward said chamber to shut it off from the outlet chamber 72, partly by suction within the channel 57, and 40 partly, as stated above, owing to the pressure in duct 38' and channel 72. Suction within the channel 56 causes the valve 46 to move off its seat, thus establishing communication between the intermediate chamber connected with the pipe 58, and the suc-

tion chamber of which the channel 44 forms part. Thus liquid from the container is drawn into the pump at every stroke of the piston, and expelled in a practically continuous stream from the outlet 61', the chamber 70 also acting as a windchest to steady and regularize the outflow of the liquid. Generally only one of the gravity valves 47 will be open, although in the special case when the container is held so that its longitudinal axis will be horizontal, both gravity valves 47 may be open at the same time. In any event, when some of the liquid has been expelled so that there is an air space in the container, the pipe 53 whose free end communicates with such air space will be shut off from communication with the suction chamber of the central valve casing, by the action of the gravity valve 47 which at that time is the upper valve. The universal connection of the swinging pipes 53 with the central valve casing enables the free ends of said intake pipes to reach practically every point adjacent to the inner surfaces of the respective heads 21 and 22, and preferably said surfaces are of spherical curvature, with the center of curvature coinciding with the center about which the respective pipe 53 swings, that is to say, with the geometrical center of the 45 respective ball 52. The guides 74 and 75 prevent the free ends of the pipes 53 from swinging over too close to the end casings 24 and 59 and from becoming wedged or stuck in the corners of the container adjacent to said end casings; otherwise, however, the movement of the pipes 53 is restrained only by the shell 20.

50 As liquid is expelled from the container, there would be considerable resistance to the operation of the pump, owing to the formation of a partial vacuum in the container, unless provision is made for admitting air to the interior of the container, in a volume corresponding to that of the liquid expelled. This air is admitted, according to the present invention, from the outside, along the piston rod 31, through the tubular projection of the gland 36, the felt washer 35, and the slot 34' of the outer cup-shaped washer 34, into the space 24^a, and then through the duct or ducts 30' into the annular space 24^b surrounding the box 30 within the chamber 24*. From this annular space the air passes into the main space of the container through the channel or channels 24^c.

55 Any liquid leaking outwardly along the piston rod 31, particularly during its outward stroke, will pass through the central opening at the inner end of the box 30 and first reach the washer 32, which will absorb such liquid. When the washer 32 has become saturated with liquid, a further leakage might reach the other loose washer 35, and by closing the pores of this outer washer 60 105

65 110

115

120

125

130

35, reduce or destroy its capacity for admitting air as described above. In order that the outer washer 35 may always remain impermeable to air, so as to act as a satisfactory air-vent, any liquid which, after saturating the inner washer 32, should reach the inner cup-shaped washer 33, passes through the slot 33' of said washer into the space 24^a, and then through the duct or ducts 10 30' into the annular space surrounding the inner portion of the box 30, and from this space through the channel or channels 24^c into the main space of the container, so as to be led back to the body of liquid therein. 15 The channel or channels 24^c therefore form not only air-inlets, but also return channels for any liquid that may leak into the space 24^a. Should a few drops of the liquid reach the slot 34' of the outer cup-shaped washer 20 34, the practically constant rush of air passing through the washer 35 and slot 34' during the operation of the pump will immediately carry such liquid back into the space 24^a and into the main part of the container. 25 The parts contained in the box 30 may be removed readily after removing (unsoldering) the plate 25, and the box 30 itself may be removed in that case by unscrewing it from the casing 24, and when this has been 30 done, the handle 27, piston rod 31, and piston 73 may be separated from the apparatus, for the purpose of renewing the piston packing, etc.

The construction is relatively simple and 35 can be manufactured at a correspondingly low cost for materials and labor, while the provision against leakage is so thorough as to secure a very high efficiency of the pumping action.

40 It will be noted that each of the tubes 29 and 58 serves alternately as a suction pipe and as a delivery pipe, and by utilizing them for this double function I am enabled to reduce the number of pipes employed.

45 After unsoldering the plate 62, at least at its outer edge, the outlet member 61 with the nozzle 61' may be removed readily, thereby affording access to the chamber 70, for the removal of the valve 64, slide 68, and 50 springs 66, 67, if desired.

Various modifications may be made without departing from the nature of my invention as set forth in the appended claims.

I claim as my invention:

55 1. In apparatus of the class described, a container, a pump located therein and comprising a barrel and a reciprocating piston, means whereby the reciprocation of said piston will cause fluid to be expelled from 60 the container, a packing box through which said piston rod extends, containing packing pervious to air, and an air-vent connection leading from a point in said packing box adjacent to said piston rod to the interior of 65 the container, whereby air will pass during

the operation of the pump, through the said packing and said air-vent, into the interior of the container and blow back into the container, along the piston rod, any liquid which may have passed outwardly along the 70 piston rod into said packing.

2. In apparatus of the class described, a container, a pump comprising a barrel located within the container, a piston reciprocating in said barrel and a piston rod extending to the outside of the container, packing pervious to air surrounding said piston rod, and a valveless air-vent channel for admitting air through the said packing along said piston rod to the interior of the container. 75 80

3. In apparatus of the class described, a double-acting pump having two compartments, a valve-casing comprising an end section formed with a channel in permanent communication with one of said pump compartments, and with two ducts communicating with said channel, a middle section provided with two delivery channels located adjacent to one of said ducts, a valve controlling the connection of one of said delivery channels either with the other delivery channel or with said duct, two chambers one of which is in permanent communication with the other duct of said end section, a suction channel and valve mechanism controlling the alternate communication of said suction channel with said chambers, and another end section fitted against the other end of the middle section and provided with a channel in permanent communication with the other pump compartment, with the other chamber of the middle section, and with the last-named delivery channel of said middle section. 90 95 100

4. In apparatus of the class described, a double-acting pump having two compartments, and a valve-casing comprising an end section formed with a suction duct and a delivery duct in permanent communication with one of said pump compartments, a middle section formed with an outlet channel and with a delivery channel adjacent to said delivery duct, a valve mechanism controlling the connection of said outlet channel with either said delivery channel or said delivery duct, said middle section also having a suction channel, and another end section having suction and delivery ports in permanent communication 110 115 120

with the other pump compartment and with said delivery channel, and valve mechanism controlling the alternate connection of said suction channel with the suction duct and suction port of the two end sections. 125

5. A fluid-container, means for expelling fluid from said container comprising a piston pump, a rod to reciprocate the piston of said pump, a packing box through which the piston rod of said pump extends, a 130

- passage leading from said packing box to the interior of said container, piston packing surrounding said piston rod and divided into two portions lying on opposite sides of the point at which said passage leads to the packing box, whereby said passage communicates with a point between said two packing portions.
6. In apparatus of the class described, a container, a piston pump located within said container, a rod to reciprocate the piston of said pump, packing for said piston rod pervious to air, and means for admitting air from the outside of the container through said packing to the interior of said container, substantially as described.
7. In apparatus of the class described, a pump, a casing provided with an outlet chamber connected with the pump, and with a nozzle leading from said chamber, a valve movable in line with the path of the pump piston and adapted to close said nozzle, a slide interposed between the pump piston and said valve, the valve and slide being formed, the one with a sleeve, and the other with a stem entering said sleeve and in sliding engagement therewith, a spring surrounding said sleeve and bearing against said valve and said slide with a tendency to separate them, and means for causing the valve to open.
8. In apparatus of the class described, a pump, a casing provided with an outlet chamber connected with the pump and having a nozzle with a tubular projection extending into said chamber inwardly, a washer surrounding said projection, a cup-shaped valve movable longitudinally of said projection and having an edge adapted to engage said washer, a washer located within the valve and adapted to engage the end of said projection, at the same time that the edge of the valve engages said washer, and means for operating said valve.
9. In apparatus of the class described, a container, a pump located therein and comprising a barrel, a reciprocating piston therein, and a piston rod extending to the outside of the container, means whereby the reciprocation of said piston will cause fluid to be expelled from the container, a packing box through which said rod extends, two spaced washers located in said box, and the outer one of said washers serving for the inward passage of air, while the inner washer serves to absorb any fluid leaking along the piston rod, and a connection from the space between said washers to the interior of the container.
10. In apparatus of the class described, a container, a pump comprising a barrel located within the container, a reciprocating piston in said barrel, and a piston rod extending to the outside of the container, means whereby the reciprocation of the piston will cause fluid to be expelled from the container, a packing box through which said rod extends, said box containing an inner and an outer washer of permeable material, with a space between said washers which is in communication with the interior of the container, and two elastic cup-shaped washers fitted between said first-named washers and provided with central apertures in permanent communication with said space.
11. In apparatus of the class described, a container, a pump comprising a barrel located within said container, a reciprocating piston in said barrel, and a piston rod extending to the outside of the container, means whereby the reciprocation of the piston will cause fluid to be expelled from the container, a packing box through which said rod extends, permeable washers located within said box at different distances from its ends, and separated by a space in permanent communication with the interior of the container, and two dished washers set between the first-named washers, the convex faces of said dished washers being in contact with each other and provided with non-circular openings in permanent communication with said space.
- In testimony whereof, I have signed this specification.

HARRY E. TUNNELL.
